6 Claims. (Cl. 196—52)

This invention relates to a process for the reduction of the olefin content of a hydrocarbon fraction. More specifically, it is concerned with a process for reducing the bromine number of a gasoline boiling range fraction to prepare a hydrocarbon fraction suitable for aviation fuel purposes.

Cracking or reforming operations generally produce gasolines which have a high initial octane number, but which have a relatively low lead susceptibility due to their high olefin content. For this reason gasolines produced by these processes are usually unsatisfactory as aviation fuel base stocks.

We have found that a gasoline of low olefin content may be obtained by contacting an olefinic gasoline substantially free of lower boiling hydrocarbons with a catalyst comprising boron oxide on a refractory supporting material such as alumina, thoria, or ceria at proper operating conditions. We have found that when the proper operating conditions are employed the fraction of the product which boils within the range of the charging material will have a bromine number less than half of that of the charging material with the resultant increase of lead susceptibility. In this manner the olefinic gasoline may be converted into a suitable aviation fuel.

It is, therefore, an object of our invention to produce a hydrocarbon fraction boiling in the gasoline range having a bromine number of less than half that of the corresponding fraction of the charge. It is a further object of our invention to produce from an olefinic naphtha a hydrocarbon product having a fraction which boils below the end point of the naphtha charge, the said fraction having a 1-C octane number with 4 ml. of tetra-ethyl lead per gallon at least 5 units higher than the corresponding leaded octane number of the charge. Furthermore, for more satisfactory use in preparing aviation fuel blends the 1-C octane number of the product with 4 ml. of tetra-ethyl lead per gallon should be in excess of 85 and preferably in excess of 90. The 1-C method is described in A. S. T. M. 614-41T.

Catalysts which we have found to be especially suitable for this purpose comprise porous associations of boron oxide and oxides of metals such as aluminum, thorium and cerium. These catalysts may be prepared synthetically by various methods; for example in the preparation of a catalyst comprising boron oxide and alumina, the alumina may be in the form of pills or granules which are placed in a saturated solution of H_3BO_3 and the excess water evaporated. Another method of

preparation is by precipitating the alumina in a boric acid solution as follows: solutions of boric acid and $AlCl_3 \cdot 6H_2O$ are mixed together and NH_3 added until the pH reaches about 7. The mixture is then slurried and the excess water driven off by heating. The NH_4Cl is driven off by calcining.

The process of this invention is conducted at a temperature of about 400° F. but below 650° F. and preferably within the range of 450° to 650° F. The pressures which are employed are such that at least a substantial portion of the material in the reaction zone is in the liquid phase and will, therefore, usually be above about 300 pounds per square inch. In general pressures below 1,000 pounds per square inch are adequate, the higher pressures being employed at the higher temperatures in order to aid in maintaining a substantially liquid phase in the reaction zone. The space velocities which are employed are below about 15 and will ordinarily range from about 0.3 to 15 unit weights of charging oil treated per hour per unit weight of catalyst in the reaction zone. The preferred range is from about 0.5 to 5 units.

In the preferred operating range of this invention the amount of cracking, as measured by the accompanying gas formation, is negligible and, therefore, almost 100% of the charge on the weight basis is recovered as a liquid. The amount of gas formation is negligible and the amount of catalyst deposit which is formed is also small when operating in the preferred range of temperature, pressure and space velocity. On the other hand, if temperatures are increased in excess of 650° F., cracking begins to take place, gas and catalyst deposit are formed in increasing amounts and in general the operation is unsuitable for our purposes.

In one specific embodiment the present invention relates to a process for reducing the olefin content of an olefin containing fraction boiling in the gasoline range which comprises contacting said fraction with a catalyst comprising boron oxide and a refractory metal oxide at a temperature of above 400° F., but below 650° F., without effecting substantial cracking and at a pressure such that a substantial portion of the hydrocarbon in the reaction zone is in the liquid phase to form a liquid product a substantial portion of which boils within the range of said olefin containing fraction and has a bromine number of less than half that of said olefin containing fraction.

The charging stock which may be employed in this process may comprise any olefinic naphtha fraction, gasoline or pure olefinic hydrocarbon

boiling in the gasoline range. Ordinarily olefinic naphtha fractions or gasolines produced by cracking or reforming operations, preferably catalytic, will be employed since these charging materials are abundant and usually possess high initial octane numbers.

The catalyst may be employed either in the form of granules, pellets or other preformed states or in the form of a finely divided powder. In case granules are employed the reactants may be continuously passed through a bed of the granular catalyst maintained at reaction conditions. If powdered catalyst is employed the catalyst may be suspended in the reactant stream and conducted through a turbulent reaction zone or through a vertical enlarged reaction zone in which the catalyst is maintained in turbulent motion by the upwardly rising reactants and conversion products.

The products from the reaction zone may be fractionated to separate a distillate of the desired end point from the bottoms. Any portion of the reaction products may, if desired, be returned to the reaction zone for further treatment.

Unlike other operations for producing aviation base stocks from olefinic hydrocarbons, the catalyst may be used in this operation for a considerable length of time without necessity for regeneration thereof. For example, times of processing may range up to about 75 hours more or less and a product having the necessary low bromine number will be continually obtainable. Normally times of processing longer than two hours are employed.

When regeneration is required it may be accomplished in situ by passing oxygen containing gas through the catalyst bed, or the catalyst may be removed to an external zone, regenerated by contact with an oxygen containing gas and returned to the processing zone for further use.

The following example illustrates the yields and quality of the aviation fuel stock which may be obtained when operating according to the process of our invention. In the following tests the charging material comprising a 280° F. E. P. gasoline was passed over three different materials, an alumina-boron oxide catalyst containing approximately 40% boron oxide, activated alumina, and a composite of alumina-molybdena. The following data were obtained:

Catalyst	Charg-ing stock	Acti- vated alumina	Alumina- Molyb- dena	Alumina- boron oxide
Temperature . . . . . ° F.	527	534	530	
Pressure pounds per square inch	800	800	800	
Weight hourly space velocity	1.4	1.5	2.3	
Time of processing hours	2	2	15	
Product distribution:				
Percent by weight of 280° F., end-point gasoline	100	97	96	77.3
Percent by weight of residue 280° F., endpoint gasoline		3	4	22.7
Bromine No.	69	65	63	24
Octane number 1-C+4 ml. tel/gal	88.9	89	89.2	98.4

In the above test employing alumina-boron oxide catalyst the gas produced was negligible and the amount of catalyst deposit was very small, being less than $\frac{1}{10}$ of 1% by weight based on the charge.

The above tests clearly show the improvement

in bromine number and lead susceptibility which is obtainable when employing the process of our invention.

We claim as our invention:

1. A process for reducing the olefin content of an olefin containing hydrocarbon fraction boiling in the gasoline range which comprises contacting said fraction with a catalyst containing boron oxide at a temperature of from about 400° F. to about 650° F. and at a pressure such that a substantial portion of the hydrocarbon in the reaction zone is in the liquid phase, to form a liquid product boiling substantially within the gasoline range and having a bromine number of less than half of that of said olefin containing fraction.

2. A process for reducing the olefin content of an olefin containing hydrocarbon fraction boiling in the gasoline range which comprises contacting said fraction with a catalyst comprising boron oxide on a refractory support, at a temperature of from about 400° F. to about 650° F. and at a pressure such that a substantial portion of the hydrocarbon in the reaction zone is in the liquid phase, to form a liquid product boiling substantially within the gasoline range having bromine number of less than half of said olefin containing fraction.

3. A process for reducing the olefin content of an olefin containing hydrocarbon fraction boiling in the gasoline range which comprises contacting said fraction with a catalyst comprising an association of boron oxide and alumina, at a temperature of from about 400° F. to about 650° F. and at a pressure such that a substantial portion of the hydrocarbon in the reaction zone is in the liquid phase, to form a liquid product boiling substantially within the gasoline range and having a bromine number of less than half of said olefin containing fraction.

4. A process for reducing the olefin content of an olefin containing gasoline which comprises contacting said gasoline with a catalyst containing boron oxide, at a temperature of from about 400° F. to about 650° F. and at a pressure of from about 300 to about 1,000 pounds per square inch gage to maintain a substantial portion of the hydrocarbons in the reaction zone in the liquid phase, to form a liquid product boiling substantially within the gasoline range and having a bromine number of less than half that of said gasoline.

5. A process for reducing the olefin content of an olefin containing gasoline which comprises contacting said gasoline with a catalyst comprising boron oxide on a refractory support, at a temperature of from about 400° F. to about 650° F. and at a pressure of from about 300 to about 1,000 pounds per square inch gage, to form a liquid product boiling substantially within the gasoline range and having a bromine number of less than half that of said gasoline.

6. A process for reducing the olefin content of an olefin containing gasoline which comprises contacting said gasoline with a catalyst comprising an association of boron oxide and alumina, at a temperature of from about 400° F. to about 650° F. and at a pressure of from about 300 to about 1,000 pounds per square inch gage, to form a liquid product boiling substantially within the gasoline range and having a bromine number of less than half that of said gasoline.
